UNITED STATES PATENT OFFICE.

ALBERT H. EMERY, OF NEW YORK, N. Y., ASSIGNOR TO THE EMERY SCALE COMPANY, OF STAMFORD, CONNECTICUT.

DYNAMOMETER.

SPECIFICATION forming part of Letters Patent No. 278,911, dated June 5, 1883.

Application filed February 5, 1881. (No model.)

To all whom it may concern:

Be it known that I, ALBERT H. EMERY, of the city, county, and State of New York, have invented certain new and useful Improvements in Dynamometers, of which the following is a specification.

The invention relates to an improved dynamometer, applicable also to purposes of weighing and gaging. It is constructed with a suspension stem and beam, a pair of connecting-rods depending from the beam and attached below to a load-beam. These parts are rigidly connected together and have limited vertical play within a suitable casing, being secured against relative lateral motion by means of flexible annular fixing-plates. On the load-beam rests a pressure-column, forming one side of a liquid-pressure chamber. The chamber base-plate is attached to the casing, and is recessed for liquid-chambers both above and below, said chambers being connected by a duct, and the upper one being of smaller area to communicate reduced pressure to its column. The double-chamber base-plate is rigidly held between the main case above and a secondary casing-ring beneath it. The load is applied to a stem swiveled in a cross-head rigidly connected to the case, through which it communicates its pressure to the chamber-piece and to the liquid therein, the latter transmitting the pressure of the weight through a pressure-column to the load-beam, and through the duct to the small chamber and its pressure-column. The latter transmits the pressure by flexible plates to a system of levers communicating with a rotary indicator to show the amount of the load, as hereinafter described. A stop-plate constructed with a flange engaging over an internal shoulder in the casing-ring is placed between the pressure-column and the load-beam, and rigidly connected to the latter, to limit the vertical play of the load-beam and its attached parts relatively to the casing. The connecting-rods move within elastic packed joints of the casing to exclude dust and moisture.

In the accompanying drawings the invention is represented in four views, numbered 126 to 128, inclusive. Fig. 126 is a front view 50 of the instrument. Fig. 126^a is a front elevation of part of the internal mechanism, show-

ing an axial section through the pressure-chamber. Fig. 127 is a side elevation, partly in section, as indicated by dotted lines in Fig. 126. Fig. 128 is a vertical section of a portion 55 of the chambers in a plane at an angle of forty-five degrees to that shown in Fig. 127.

901 represents a suspension-stem passing through a suspension-beam, 902, which, with the said stem, has limited vertical play within the case 903, and is fixed from lateral motion therein by an annular plate, 904, fastened at its outer edge to the neck of the case, and at its inner edge to the beam. This beam 902 may be secured against lateral motion with 60 reference to the case 903 by any suitable packing or other means, such that there shall be very slight or no lateral movement permitted, and at the same time the small longitudinal movement shall be but slightly resisted. A 70 rubber or other elastic ring might be used for this purpose; but the method here shown of securing them by flexible metallic plates is preferable. Lock-nuts 906 fix the stem 901 to the beam. Two rods, 905, are fixed to the 75 beam 902 and extend down completely through the case, as shown. A load-beam, 907, is fixed by nuts 908 to the rods 905, being tightly clamped against shoulders on said rods by the action of the nuts. The load-beam thus fixed 80 to the suspension-stem, suspension-beam, and connecting-rods is fixed against lateral movement in the case by a thin flexible plate, 909, secured at its outer edge to a casing-ring, 910, and at its inner edge to the load-beam. 85

911 represents a base-plate recessed on both its upper and under surfaces to form liquid-chambers, as hereinafter described.

912 are studs screwed into the case 903 and formed with shoulders, whereby they fix rigidly to the case the casing-ring 910 and chamber-base 911.

913 is a load cross-head clamped to the lower ends of the fixing-studs 912 by nuts 914, and forming an attachment for a load-stem, 915, 95 which is swiveled therein, being secured by a nut, 916, and washer 917. A pin, 918, fastens the nut 916 to the washer 917, so as to cause them to turn together as the stem swivels on the cross-head.

919 is a stop-plate fastened by a screw, 920, to the load-beam 907, and formed with a pro-

jecting flange or shoulder, as clearly shown in Fig. 127, to limit the upward movement of the case by the contact of the said shoulder with an inwardly-projecting flange or shoulder on the casing-ring 910 when the instrument is relieved of a load.

921 is a pressure-column resting, through the medium of the plate 919, on the beam 907, and secured by a flexible metallic diaphragm, 922, to the chamber-base 911, a tight chamber being thus formed between the base 911 and the column 921. A column, 923, and flexible diaphragm 924 cover the liquid-chamber of smaller area on the opposite side of the double-chamber base 911, the two chambers being connected by a liquid-duct, 973, (shown in dotted lines in Fig. 127 and in full lines in Fig. 128,) so that when a load is applied to the case 903 pressure on the liquid in the lower chamber, 20 between the base 911, which is fixed to the case, and the column 921, which rests on the suspension-yoke 902 905 907, will be communicated through the duct to the smaller chamber above, developing a pressure reduced in 25 its aggregate by the proportionately smaller area of the chamber.

925 is a diaphragm-ring which bears upon the outer edge of the diaphragm 924. This separate ring may be dispensed with, the case 30 903 being formed to rest directly on the diaphragm 924.

926 are elastic rings set partly in the load-beam 907 and covering the opening in the casing-ring 910 around the rods 905. The said 35 elastic rings, while covering the openings, permit the slight relative motion of the parts without friction. These rings 926 may be used in the same manner in machinery where the liquid-chamber piece 911 is dispensed with, 40 and exclude air, dust, &c., from the case 903 equally well, the case 903 in this instance resting directly on the ring 910.

927 is a sealing-plug closing the duct 974, through which the liquid-chambers and connecting-duct 973 are filled.

975 is a transverse duct permitting the escape of air from the chambers while they are filled with liquid. The upper pressure-column is preferably formed in two parts, the upper part, 928, being connected by a clamp, 931, and a flexible transmitting-plate, 932, to the load-lever 933, which is fulerumed by the flexible plate 934 and clamp-plate and screw 935 to the fulerum-block 930, the latter being secured by screws 929 to the case 903. A weight applied to the case by the load-stem 915, depressing the chamber-base 911, presses liquid up through the duct 973 into the chamber above, developing pressure upward on the column 923 928 and load-lever 933. From the load-lever 933 pressure is transmitted through a flexible plate, 936, and clamps 937 938 to a secondary lever, 942, fulerumed by a compound flexible joint formed by thin plates 939 65 939^a and clamp 940.

941 is a clamp which fixes the plate 939 to

the transmitting-lever 942, and 941^a a clamp which fixes the plate 939^a to the case.

943 represents a fixing and resisting plate or plates fastened by an adjustable clamp or 70 clamps, 944, to the fulerum-block 930, and by a clamp, 945, to the load-lever 942.

946 represents a temperature-spring fastened by a clamp-plate, 947, to the back part of the secondary load-lever, and to the case by a 75 temperature and adjusting rod, 948, which is formed wholly or in part of metal more or less expansible than that of the case, in order to counteract automatically the effect of changes in temperature, as may be necessary. The rod 80 948 is screwed within the case, as shown in dotted lines in Fig. 126, for the purpose of setting it up or down to vary the pressure of the spring on the lever, and to set the indicator hereinafter described.

949 is a transmitting-plate fastened by a clamp, 950, to the secondary lever 942, and by a clamp, 952, to the fulerum-block 951 of a transmitting-lever, 953, which is fastened to the said fulerum-block by screws 954. A 90 flexible fulerum-plate, 955, is fixed to the fulerum-block 951 by screws 954 and 954^a, and to a fulerum-bracket, 956, by a clamp, 957. The bracket 956 is fastened to a lug, 986, on the case by a screw, 958. The fulerum-block 951 95 is connected to the case 903, either directly or through the medium of the bracket 956, by the thin flexible plate 959, attached to the said fulerum-block by a clamp, 960, and to the case 903 or bracket 956 by a clamp-plate, 961. 100 From the lever 953 rotary motion is imparted to the indicator 966 by a band, 962, fastened to the transmitting-lever 953 by a clamp-plate, 963, and coiled on a drum, 964; on the shaft 965 of the indicator 966. The shaft 965 runs in 105 jeweled bearings on the brackets or standards 967 and 968, screwed to the block 930.

969 is a hair-spring attached at its respective ends to the indicator-shaft, and to a pin, 969^a, on the lever 942. The hair-spring offers a 110 slight resistance to the motion of the indicator and serves to keep the connections taut.

970 is an annular dial, in front of which the indicator works.

971 is a door-frame, and 972 a glass fixed 115 therein.

976 is a stud screwed in the lever 942, constituting an adjustable stop to limit the downward motion of the transmitting-lever 953.

977 is a stud screwed in the beam 902, projecting downward and constituting an adjustable stop to limit the upward movement of the lever 953.

The fixing-plate 909 may be fastened to the load-beam 907 by packing, as shown, or by 125 clamping it with the stop-plate 919 and screw 920. If preferred, the stop-plate 919 may be entirely dispensed with, the pressure-column 921 resting directly on the load-beam 907.

Elastic diaphragms may be substituted for 130 the packing 926, so as to seal the casing without friction.

By fixing the moving parts against lateral motion at their upper and lower ends they are made steady in their vertical motion. By doubling the levers, as shown, and permitting the connections 905 to work between them, the strains are taken centrally without any lateral pressure, which would tend to produce unequal wear and uncertainty in the action of the instrument.

If it be desired to adapt the machine for optional use, either horizontally or vertically, a counterbalancing-weight must be connected with the lever 953, or some other moving part, to neutralize the action of gravity when the machine is used vertically; otherwise the indications will vary in the different positions of the machine. Counterbalancing-weights are described in other applications.

Referring to Fig. 127, the diaphragm 924 is shown annular, and secured to the chamber-base 911 and pressure-column 923 by solder. This diaphragm has been usually made of brass. When in the annular form shown, or when extending over the whole area of the chamber, it has heretofore been made of one or several corrugated plates of sufficient strength to withstand the pressure of the liquid, and by its bending to communicate motion through various kinds of mechanism to the indicator-needle; but I prefer to make this as shown in Fig. 126^a, where the main pressure of the liquid, from its action on the upper side of its chamber in the base 911, is transmitted directly to the pressure-column 923 through a flat tempered steel plate, 924^a, which seals the chamber 911 on its upper side, and is combined with the said chamber and column 923 and ring 925 in such a way that the lower end of the column 923 projects slightly below the face of the ring 925, and thereby gives some considerable pressure on this diaphragm 924^a when the machine is not loaded, as by thus setting it the diaphragm will remain nearly flat throughout the whole loading of the machine from the least to the greatest loads, thereby giving much less strain on the diaphragm and much more uniform reading of the indicator than are obtained by other forms of diaphragms or methods of setting. It will be readily seen that by making and setting the diaphragm in this way I am able to use very thin flat tempered steel plates with very narrow spans, and adapt the machine to endure large pressures acting directly on the pressure-column, where I am enabled to measure them much more accurately than heretofore, and with very great uniformity of readings of the indicator. To enable me to seal the chamber 911 securely without solder, I make use of the sealing ring or rings 925^a, usually made of soft brass, put in as shown in Fig. 126^a, which rings must be sufficient in thickness to prevent the chamber-piece 911 from pressing directly against the fulcrum-block 930, when secured firmly in its seat by screws. (Not herein shown.) In using this combination of the plate 924^a and pressure-column

923 the latter must be secured very carefully against lateral motion and without friction, which is here done by means of the steel diaphragm 924^a, attached to the column 923 by the screws 923^a, or other suitable means. In this case the outer part of this diaphragm is secured by the pressure between the ring 925 and the fulcrum-block 930, produced by the screws (not here shown) which secure the chamber-base 911 to the fulcrum-block 930. In order that this method of making and setting the diaphragm 924^a shall work with the greatest efficiency, it is necessary to so connect the pressure-column 923 with such parts that even with the largest pressures from the liquid beneath it it will have only very slight motion while the indicator moves throughout its whole stroke, and to provide for the accurate measuring of the pressure on this column it is best made of one piece of steel, and with connections, as shown in Fig. 126^a, where the fulcrums 932, 934, 936, and 939 are all of tempered steel, and secured against backlash to levers 933 and 942; 933 is a solid steel lever, and 942 is a skeleton lever. Both ends of the movable fulcrum-plate 932 are driven or pressed very tightly in grooves 932^a and 932^b, cut for them in the pressure-column 923 and lever 933, while the fixed fulcrum-plate 934 has its lower end firmly pressed in a groove, 934^a, cut for it in the lever 933, and its upper end is firmly secured in a recess in the fulcrum-block 930 by the clamp-plate 935. The fulcrum-plates 936 and 939 are secured in a similar manner—939, Fig. 126^a, being a single plate taking the place of 939^a and clamp-plates 940 shown in Fig. 126. The steel plate 943 shown in Fig. 126^a is firmly clamped at its right-hand end to the lever 942 by the clamp 945, and at its left-hand end to the lever 933 by the clamps 944^a, instead of to the fulcrum-block 930 by clamp 944, as in Fig. 126. By making it in this way the action is much better than when it is so short as to fasten to the said fulcrum-block 930, and it secures the lever 942 against longitudinal and lateral motion equally well. The lever 933 and spring 943 must both have clearance-holes for the rods 905, and the clamp 944^a may be put either to the right or left of the left-hand rod 905. This spring 943, acting through the levers 942 and 933 and their fulcrums, receives a large part of the load on the pressure-column 923 from the load on the machine.

The above-described invention is obviously applicable to the purposes of pressure-gages and weighing-machines as well as to dynamometers.

Whatever novel subject-matter I have set forth and not claimed or attempted to claim herein I have claimed or attempted to claim in other applications or have reserved to be claimed in future original applications.

The following is here claimed as new:

1. The combination of the suspending-beam 902, dynamometer or gage case 903, and fixing-plate 904, substantially as set forth.

2. The combination of the suspending-stem 901, suspending-beam 902, and case 903, the beam being within the case and packed against dust and lateral motion, substantially as and for the purposes set forth. 5
3. The combination of the suspending-beam 902, case 903, and suspending-rods 905, the beam being within the case and packed against dust and lateral motion, substantially as and for the purposes set forth. 10
4. The combination, with the case 903, of the suspending-beam 902, suspending-rods 905, and load-beam 907, substantially as and for the purposes set forth. 15
5. The combination, in a dynamometer, of the casing-ring 910, thin flexible fixing-plate 909, and load-beam 907, as set forth. 20
6. The combination of the load-beam 907, fixing-plate 909, casing-ring 910, stop-plate 919, and screw 920. 25
7. The combination of the load-beam 907, pressure-column 921, pressure-diaphragm 922, and chamber-base 911. 30
8. The combination of the fixing-studs 912, casing-ring 910, chamber-base 911, and case 903. 35
9. The combination of the cross-head 913, fixing-studs 912, and case 903.
10. The combination of the swiveled load-stem 915, cross-head 913, and fixing-studs 912 with the case 903. 40
11. The double-chambered base-plate 911, in combination with the two pressure-columns 921 923, diaphragms 922 924, and casing 910 903. 45
12. The combination of the packing-rings 926, suspending-rods 905, load-beam 907, casing-ring 910, and case 903, either with or without the intervening chambered plate 911. 50
13. The combination of the chamber-base 911, flexible sealing-plate 924^a, pressure-column 923, compression fulerum-plate 932, and load-lever 933, substantially as and for the purposes set forth. 55
14. The combination of chamber-base 911, plate 924^a, casing-ring 925, and pressure-column 923, projecting below the face of the casing-ring 925, thus causing initial pressure on the said column 923, for the purpose of obtaining a uniform action of the gage. 60
15. The sealing-ring 925^a, in combination with the chamber-base 911, diaphragm or plate 924^a, casing-ring 925, and pressure-column 923, as and for the purposes set forth. 65
16. The diaphragm 924^b, in combination with the casing-ring 925 and pressure-column 923, the said diaphragm being secured to the said column, as and for the purposes set forth. 70
17. In a weighing-machine, gage, or dynamometer, a flexible fulerum-plate secured by forcing it at either end, under pressure, into a groove forming a seat for it, substantially as and for the purpose set forth. 75
18. The combination of the pressure-column 928, having groove 932^a, and lever 933, having groove 932^b, with the fulerum-plate 932, secured in said grooves by pressure, as set forth. 80
19. The combination of the fulerum-block 930, lever 933, having groove 934^a, with the fulerum-plate 934, secured in said groove by pressure, as set forth. 85
20. The combination of the lever 933, fixing and resisting spring 943, and lever 942, as set forth. 90
21. The combination of a flat metallic sealing plate or diaphragm, 924^a, pressure-column 923, fulerum-plate 932, lever 933, fulerum-plate 934, and fulerum-block 930, as set forth. 95
